UNITED STATES PATENT OFFICE.

PATRICK HAMILL, OF JEROME, PENNSYLVANIA.

RAIL CONNECTION.

1,127,885.

Specification of Letters Patent.

Patented Feb. 9, 1915.

Application filed July 19, 1912. Serial No. 710,311.

To all whom it may concern:

Be it known that I, PATRICK HAMILL, a citizen of the United States of America, residing at Jerome, in the county of Somerset and State of Pennsylvania, have invented certain new and useful Improvements in Rail Connections, of which the following is a specification, reference being had therein to the accompanying drawing.

This invention relates to a rail connection and more particularly to a protecting device for the bond between the abutting or confronting ends of two rails.

The primary object of my invention is to provide a bond protecting device in the form of a splice-bar or fish plate that has the edges thereof recessed to provide clearance for an electric bond or wire connecting the abutting or confronting ends of rails.

Another object of this invention is to provide a rail joint with a splice-bar that will protect and retain in place an electrical bond that connects the abutting or confronting ends of rails, the electric bond having the ends thereof firmly anchored in the webs of the rails, whereby an electrical connection will be established under ordinary and existing condition.

A further object of this invention is to provide a rail connection that is simple in construction, easy to install, free from injury by the ballast of a road bed, and highly efficient for the purposes for which it is intended.

With the above and other objects in view, the invention resides in a novel construction, combination and arrangement of parts to be hereinafter specifically described and then claimed.

Reference will now be had to the drawing, wherein:

Figure 1 is a side elevation of a rail connection. Fig. 2 is an end view of the same. Fig. 3 is a cross sectional view of a rail connection, and Fig. 4 is a perspective view of a portion of the splice-bar forming the projecting device for the electrical bond of rails.

The reference numerals 1 and 2 denote the webs of rails 3 that confront or abut whereby the ends of said rails can be connected together. The webs 1 and 2 are provided with transverse openings 4 and the sides of said rails are braced by splice-bars 5 and 6, said bars having openings 7

aligning with the openings 4 of the rails 3 to receive bolts 8 that are provided with nuts 9, to retain the splice-bars 5 and 6 in engagement with the webs 1 and 2 of the rails 3.

The splice-bar 6 has a lateral flange 10 thereof of a greater width than the flange of the splice-bar 5, whereby the lateral flange 10 will extend over and overhang the base flanges 11 of the rails 3. The longitudinal edge of the flange 10 is hook shaped in cross section or has a longitudinal groove 12 extending from one end of the splice-bar to the opposite end thereof, the ends of said grooves being in communication with cut away edges 13 at the ends of the splice-bar. The cut away edges 13 are at the inner sides of the splice-bar and these cut away edges coöperate with the grooves 12 in providing clearance for an electric bond or wire 14 that is arranged in the groove 12 with the ends thereof extending upwardly under the cut away edges 13 of the splice-bar. The ends of the bond or wire 14 extend into openings 15 provided therefor in the webs 1 and 2 of the rails 3, and the ends of the bond or wire 14 are retained within the openings 15 by small wedges 16 or other fastening means.

To permit of easy access being had to the openings 15, also to provide clearance for the wedges 16 or the fastening means employed in connection with the ends of the bond or wire 14, the ends of the splice-bars 5 and 6 are recessed or grooved, as at 17, the recesses 17 of the splice-bar 6 being in communication with the cut away edges 13 of said splice-bar.

From the foregoing it will be observed that the splice-bar 6 practically incloses the bond or wire 14, said splice-bar clamping the bond against the sides of the rails 1 and 2 and preventing said bond from becoming accidentally displaced, due to vibrations of the rails 3 or to ballast being tamped or thrown against the sides of the rails.

The rail connection possesses advantages that will be apparent to those familiar with the bonding of rails, and while in the drawing there is illustrated a preferred embodiment of the invention, it is to be understood that the structural elements are susceptible to such changes as fall within the scope of the appended claim.

When the plate is properly placed and

the bond put in position, the wheels of the cars cannot cut the bond.

What I claim is:—

In a rail connection, the combination with
5 a pair of rails with splice bars connecting
the ends of said rails, one of said splice
bars having an outer edge portion project-
ing from the rail bases and disposed oppo-
site the longitudinal edge of the rail bases,
10 that portion disposed opposite said edge
provided with a longitudinally extending
groove, the splice bar provided with the
longitudinal groove having the inner face
at each end thereof formed with a groove
15 extending from an end of the longitudinal
groove and terminating at the upper edge
of the said splice bar, said grooved splice

bar having each end in proximity to
top edge slotted through, said slots inter-
secting the grooves at the ends of the splice
bar to provide access to the rails opposite
the slots, a bond mounted in said grooves
and extending opposite said slotted portions
and into the webs of the rails, and means
for maintaining the ends of said bond in 25
engagement with said rails opposite the
slots.

In testimony whereof I affix my signature
in the presence of two witnesses.

PATRICK HAMILL.
